UNITED STATES PATENT OFFICE.

JAMES H. BOYE, OF CHICAGO, ILLINOIS, ASSIGNOR TO THE BOYE NEEDLE COMPANY, OF CHICAGO, ILLINOIS, A CORPORATION OF ILLINOIS.

TATTING-SHUTTLE.

1,222,176.

Specification of Letters Patent. Patented Apr. 10, 1917.

Application filed November 10, 1915. Serial No. 60,742.

To all whom it may concern:

Be it known that I, JAMES H. BOYE, a citizen of the United States, residing at Chicago, in the county of Cook and State of Illinois, have invented a new and useful Improvement in Tatting-Shuttles, of which the following is a specification.

The present invention constitutes an improvement upon the tatting shuttle described 10 in my pending application No. 57127, filed Oct. 21, 1915.

The primary object is to provide an improved device of such construction as to facilitate the removal or withdrawal of the 15 bobbin, either for re-winding purposes, or for the purpose of substituting another bobbin containing a different thread.

A further object is to so construct the improved device as to provide the shuttle 20 proper with a thread-hook.

The invention is illustrated in its preferred embodiment in the accompanying drawing, in which—Figure 1 is a side view of a tatting shuttle constructed in accordance with this invention; Fig. 2, a plan view 25 of the device; Fig. 3, a view similar to Fig. 1, but showing the bobbin withdrawn from the housing afforded by the sides of the shuttle; Fig. 4, a plan view with the bobbin in 30 the position shown in Fig. 3; Fig. 5, a side view with the shuttle reversed from the position shown in Fig. 1; Fig. 6, an enlarged broken sectional view, illustrating the manner in which the sides, or bows, of the shuttle 35 are united at their end portions, this view showing also the pivotal connection of the swinging arm which carries the pivot for the bobbin; Fig. 7, an enlarged broken 40 sectional view taken as indicated at line 7 of Fig. 1; Fig. 8, an enlarged broken view of the arm which carries the bobbin or spool, this view illustrating the furcated expandible 45 pivot, or trunnion, upon which the spool is demountably carried; and Fig. 9, a broken sectional view of a slight modification.

In the construction illustrated, A represents the shuttle proper, or the frame of the device; B, an arm pivotally mounted in said frame; and C, a removable spool or bobbin 50 carried by the arm B, the arm and spool being normally housed between the bows of the shuttle.

The frame A preferably comprises a pair 55 of resilient, pointed side members or bows, 1 and 2, whose extremities are permanently

joined together. In the illustration given the bows are of metal and are provided at their extremities with inwardly-struck embossments 3. One of the bows is provided at the embossments 3 with perforations 4; 60 and the other bow is provided at the embossments 3 with inwardly-struck lugs 4^a, which pass through the perforations 4 and are clenched. The lugs 4^a after clenching, are disposed within the depressions afforded by 65 striking the metal inwardly to form the embossments 3. After the bows are united in the manner indicated in Fig. 6, the tips are touched with solder, as indicated at 5, to give the extremities of the shuttle the character 70 of an integral formation.

It is preferred to notch the edges of the pointed extremities of the bows at one end of the shuttle to provide a small thread-hook 6, which is undercut so as to provide a 75 distinct barb, which may be used to engage the thread and pull it through the loop.

The arm B may be formed of resilient sheet metal, such as brass. The arm is preferably of the angular form shown, having 80 the extremity of its long arm connected, by a pivot 7, to one bow of the frame A, near one end of the device. The short arm or angular projection of the member B carries a laterally projecting pivot or trunnion 8, 85 upon which the bobbin or spool C is demountably carried. The trunnion 8 may be formed by providing the short member 8^a of the swinging arm or link B with lugs or 90 projections 8^b, which are bent at right angles, so as to extend laterally from the member 8^a, as indicated in Fig. 8. The furcations 8^b are made concavo-convex, and the extremities 95 are bent apart, as indicated at 8^c. At the elbow of the link B is provided a small thumb-piece 8^d, which may be used to swing the link from its normally housed position. In the housed position, the thumb-piece 8^d 100 engages one edge of one of the bows of the shuttle, thus acting as a stop. In this position, the spool C is properly centered and engages an inwardly-struck central embossment 9, with which the side member 2 of the shuttle is provided.

The spool C comprises a short barrel 10 105 and flanges 11. The spool may be slipped onto the trunnion 8, the furcations 8^b forming the trunnion, yielding somewhat as the spool is forced onto the trunnion, and the projections 8^c afterward serving to prevent 110

accidental dislodgment of the spool. It will be understood that the embossment 9 serves to properly center, and hold in centered position, the trunnion 8, when the link B is 5 swung to the housed position, the stop 8^a coming into engagement with one edge of the bow 1 of the shuttle at the instant the open end 8^b of the trunnion 8 springs into engagement with the embossment 9. The 10 side members 1 and 2, owing to their resilient character, will spring apart as the spool is forced to the centered position, thus the projection 9 serves as a catch or retainer to hold the spool properly centered, but with- 15 out interfering with the revolution of the spool. Inasmuch as the side members or bows of the shuttle are held separated slightly more than when the spool is with- drawn from the housing, it will be evident 20 that the spool is frictionally held, so that it will not rotate too freely in the tatting operation, and will hold the thread from unwrapping in case the shuttle is dropped.

The tatting operation is carried on in the 25 usual manner. When desired, the link or swinging mounting B may be withdrawn from the housing, and a fresh supply of thread may be wound upon the bobbin C; or, if desired, the spool or bobbin may be 30 removed and replaced by another spool containing a different kind of thread. The thread, in the illustration, is designated 13.

It will be noted from Fig. 4 that the spool C is free at one side when the mounting B 35 is in the unsheathed position. This enables thread to be wound readily upon the spool.

The construction of the device is such that the spool or bobbin will be automatically 40 centered in the operation of sheathing it. In other words, it is only necessary to swing the link B inwardly until the thumb-piece 8^a engages the shuttle frame, and the spool will be automatically centered and properly 45 retained in the frame until it is forcibly withdrawn. In the modification shown in Fig. 9, the construction is similar to that described, except that the link B' (which corresponds with the link B) is provided with 50 an embossment 9^a which co-acts with a spool-centering perforation 1^a with which the bow 1 is provided. In this modification, the embossment 9 of the bow 2 is dispensed with.

The foregoing detailed description is given for clearness of understanding only, 55 and no unnecessary limitation should be understood therefrom, but the appended claims should be construed as broadly as permissible in view of the prior art.

What I regard as new and desire to secure 60 by Letters Patent is:

1. A tatting shuttle comprising a pair of bows, a link pivotally connected therewith and provided with a laterally projecting trunnion at its free end, and a spool de- 65 mountably carried by said trunnion.

2. A tatting shuttle comprising a pair of bows, a link pivotally connected therewith and provided with a laterally projecting, ex- 70 panding trunnion, and a spool demountably carried by said trunnion.

3. A tatting shuttle comprising a pair of resilient bows having their end portions connected, a link pivotally connected therewith and adapted to be sheathed between the 75 bows, said link provided at its free end with a laterally projecting trunnion adapted to be held between said bows by the resilience of the bows, and a spool mounted on said trunnion.

4. A tatting shuttle comprising a pair of resilient bows, one of which is provided with a spool-centering device, a link pivotally connected with one of the bows and provided with a laterally projecting trunnion, and a 85 spool carried by said trunnion.

5. A tatting shuttle comprising a pair of resilient bows, having connected extremities, one of the said bows being provided with a spool-centering device, a link pivotally connected with one of said bows, and equipped with a laterally projecting trunnion, and with a thumb-piece, and a spool mounted on 90 said trunnion.

6. A tatting shuttle comprising a pair of 95 resilient bows, having connected extremities, one of said bows having a spool-centering device, an angular link pivotally connected with one of the bows and adapted to be housed between the bows, said link provided 100 with a laterally projecting trunnion, and a spool mounted on said trunnion.

JAMES H. BOYE.

In presence of—

A. C. FISCHER,
K. O'NEILL.
